UNITED STATES PATENT OFFICE.

LINUS H. SHAW, OF BROCKTON, MASSACHUSETTS.

ANTI-SNORING DEVICE.

SPECIFICATION forming part of Letters Patent No. 460,451, dated September 29, 1891.

Application filed February 6, 1891. Serial No. 380,529. (No model.)

To all whom it may concern:

Be it known that I, LINUS H. SHAW, a citizen of the United States of America, and a resident of the city of Brockton, in the county 5 of Plymouth, in the State of Massachusetts, have invented a certain new and useful Improved Anti-Snoring Device, of which the following is a full, clear, and exact description.

The object of this invention is to provide 10 means to be worn by persons when sleeping to prevent snoring.

The means of this invention, and which for convenience is designated an "anti-snoring device," consist, in substance, of a band to 15 surround and to be held on the neck of the person, a band to cross the front, and a band to cross under, and each thereof to extend around the sides of the chin, in combination with mechanism composed, essentially, of a 20 semicircular frame, at its opposite ends pivoted to opposite sides of said neckband and projected forward under the chin, a slide-bar at each end, held on and free to slide along said frame, and yielding spring-arms, one at 25 each side of the chin and both held on said slide-bar, and each at its upper end portion having an arm pivoted thereon and to which said chin-bands at their opposite ends are fastened, all substantially as hereinafter de- 30 scribed.

In the drawings forming part of this specification, Figure 1 is a side view of the anti-snoring device of this invention and illustrated as in use. Fig. 2 is a front view of 35 Fig. 1. Fig. 3 is a plan view of the device.

In the drawings, A is the neckband.

B and C are the two chin-bands.

D is the semicircular frame.

E is the slide-bar, at its opposite ends held 40 on and free to move along the frame D.

F F² are the side spring-arms, held on said slide-bar, and G G² are crank-arms, each pivoted to one of said side arms at its upper end portion, and to these arms the opposite 45 ends of the two chin-bands are attached.

The neckband A may be any band which is suitable to surround and to be held on the neck without strain on or annoyance to the wearer—as, for illustration, a split spring- 50 band of metal suitably covered or otherwise

protected or the usual neckband of the night-gown, &c. The semicircular frame D at its opposite ends is hung on pivots *a* of said neckband and thence extends forward, so as, with the neckband in position on the wearer, to lie 55 under and below the chin. The slide-bar E at its opposite end portions has tubular blocks *b b*, which engage and so hold the slide-bar on and adapt it for movement along said frame D, and, again, H is a rod that extends lengthwise 60 along the upper side and is supported in ear-pieces *d d* at each end portion of said slide-bar.

The spring-arms F F² are on the opposite sides of the chin, one on each side, and, as particularly shown, they are continuous with 65 reverse coils *f*, surrounding the rod H, held on slide-bar, as has been explained, and at their central portion looped about the frame D, all so that elasticity and spring are imparted thereby to the arms to resist strain or ten- 70 sion thereon.

The chin-bands may be made of cloth or other like or suitable material and the band B adapted to cross the front and the band C to cross under and both to extend around on 75 each side of the chin, and at their opposite ends they are fastened in any suitable manner to the crank-arms G G², pivoted, as de- 80 scribed, to the upper ends of the side spring-arms.

In the practical use of the device explained the chin-bands serve to hold the chin firmly yet yieldingly against movement, and thereby the mouth held from opening and so snoring is prevented, it being very well 85 known that snoring results from an opening and consequent breathing through the mouth instead of through the nostrils. The connection of these chin-bands with the neckband A, which has been described, plainly 90 allows perfect freedom of movement of the device should strain come on it in any direction because of changes in position of the head or body of the wearer while sleeping.

Having thus described my invention, what I 95 claim, and desire to secure by Letters Patent, is—

The combination, with a neckband A and front and under chin-bands B C, of a frame D, hung on opposite sides of and projected 100

from said neckband, a slide E, held on and free to move along said frame D, and spring-arms F F², held on and projected from opposite end portions of said slide E and having 5 said chin-bands attached to their outer ends, substantially as described, for the purpose specified.

In testimony whereof I have hereunto set my hand in the presence of two subscribing witnesses.

LINUS H. SHAW.
